E. LUDORF

PROJECTILE FOR FIREARMS

Filed May 13, 1921

UNITED STATES PATENT OFFICE.

ERNST LUDORF, OF BERNE, SWITZERLAND.

PROJECTILE FOR FIREARMS.

Application filed May 13, 1921. Serial No. 469,276.

To all whom it may concern:

Be it known that I, ERNST LUDORF, a citizen of the German Republic, residing at Berne, Effingerstrasse No. 6^a, Switzerland, 5 have invented new and useful Improvements in Projectiles for Firearms, of which the following is a description.

The present invention relates to a projectile which contains the whole or part of its 10 charge and which may be used for hand weapons, machine guns, etc.

The object of the invention is to provide a projectile which contains the maximum charge in a comparatively small space and 15 which is simple in construction and absolutely reliable in use.

With the foregoing and other objects in view this invention consists in such novel features of construction, combination and 20 arrangement of parts as will be hereinafter more fully described, illustrated in the accompanying drawings, and claimed.

In describing the invention in detail reference will be had to the accompanying 25 drawings wherein like characters designate like and corresponding parts throughout the several views, and in which:

Figs. 1, 2, 4 and 5 is each a longitudinal section through a form of the new projectile. 30

Fig. 3 shows a modified construction of the projectile shown in Fig. 2.

In Fig. 1 of the drawing 1 denotes the shell of hard metal such as steel designed for 35 penetration and terminating in an elongated point 2 of approximately parabolic shape. Within the shell 1 there is a core 3 of soft metal, a disk 10 and the explosive material 9 forming the propelling charge of the projectile. The inner wall 8 of the shell is 40 tapering, the thickness of the wall is about equal to the thickness of the head 2 and diminishes gradually toward the hind end of the shell 1. At the hind end the shell is 45 closed by a bottom 11 made of thin sheet metal with low melting point of celluloid, impregnated paper or similar material which is easily ignited. The bottom is joined to the shell 1 by suitable means; it 50 may be pressed into a collar 4 which serves as a driving band. The collar becomes molded into the rifling of the barrel as soon as ignition begins. Between the bottom 11 and the disk 10 a rod 13 is provided running in the centre line of the projectile and 55 consisting of hard explosive material. The

rod 13 has a central bore 12 and carries at its end adjacent the bottom 11 the primer 14. The space between the rod 13 and the shell is filled with loosely packed explosive material. If the firing pin of the gun strikes the primer 14 ignition of the propelling charge takes place. The bore 12 facilitates the rapid consummation of the charge. The rod 13 offers sufficient resistance to the firing 60 pin to ensure the ignition of the primer.

In Fig. 2 a modified construction is shown which differs from that shown in Fig. 1 in that the whole propelling charge 15 forms one solid body fitting the hollow of the shell 70 exactly. The body 15 is provided with several bores 16 which facilitate the rapid consummation of the propelling charge.

The body may be built up of a number of 75 perforated disks.

To increase the propelling charge without increasing the size of the shell 1 the bottom may be made to form a cap 17 of celluloid, paper, etc. The cap 17 covers the end of the propelling charge projecting from the 80 shell 1 and carries at its inner side the primer 19. The cap 17 is fixed to the shell 1 by means of a flange engaging the collar 4.

In Fig. 4 another form is shown in which the central rod 20 is movably arranged in 85 the centre of the shell 1. The rod 20 which consists of hard explosive matter and which constitutes part of the propelling charge is held by bottom 11 and carries at its inner end the primer which is at some distance of 90 a projection 21 of the disk 10. The space around the rod 20 which consists of explosive material is filled with loosely packed explosive material. If the firing pin of the gun strikes the centre of the bottom 11 the 95 rod 20 is displaced in axial direction and strikes against the projection 21 igniting thereby the primer.

As shown in Fig. 5 the rod 20 may be placed in the bore of the body 15 of hard 100 explosive material fitting the shell 1. The primer is again placed at the inner end of the rod 20 opposite to the projection 21. To prevent untimely ignition the rod 20 may be held not only by the bottom but by 105 sliding springs or some braking device preventing accidental displacement of the rod 20 within the shell. The shell 1 is provided at its fore portion with a band 22, replacing the collar 4 at the hind end of the 110 shell.

The parts 15 and 20 may be provided with

igniting material which when the parts 15, 20 rub on each other ignites. The primer however, may be made of any suitable known material.

5. If ignition starts in the interior of the shell the propelling charge is more rapidly consummated and its effect is considerably increased.

I wish to point out that I do not limit my 10 invention to the particular construction as described, as various details of construction may be varied without departing from the spirit of my invention.

What I wish to secure by Letters Patent is:—

1. A projectile having a head and a shell for an explosive charge, said head and said shell having an integral continuous wall extending from the point of the head to the 20 rear end of the shell, and said head being hollow and being provided with a core.

2. A projectile having a head and a shell for an explosive charge, said head and said shell having an integral continuous wall extending from the point of the head to the 25 rear end of the shell, said head being hollow and being provided with a core, and a disc in said shell at the base of said core.

3. A projectile having a head and a shell for an explosive charge, said head and said 30 shell having an integral continuous wall extending from the point of the head to the rear end of the shell, said head being hollow and being provided with a core, a disc in said shell at the base of said core, said 35 disc having a projection, and said shell having a rod extending through the charge chamber from the base of the shell to the disc, and arranged with its front end opposite said projection. 40

In witness whereof I affix my signature.
ERNST LUDORF.
